TUCKER MECHANISM

Frederick H. Peterson, Watertown, Conn., assignor to The Patent Button Company, Waterbury, Conn., a corporation of Connecticut

Application April 9, 1942, Serial No. 438,315

1 Claim. (Cl. 218—6)

My invention relates to new and useful improvements in button attaching machines, and more particularly to what is known as a tucker mechanism.

The invention in its broadest aspect is similar to that type of tucker mechanism or button attaching machine as shown and described in the patent of F. H. Peterson, No. 2,265,575, issued December 9, 1941.

Broadly speaking, a tucker mechanism of a button attaching machine is that part of the mechanism that advances the tack, after it leaves its chute, to the attaching station directly under the button, where, on the descent of the plunger, the button is forced downwardly, and consequently the tack prong is forced through the cloth into the button to thus securely fasten the button to the cloth.

The tucker mechanism, however, as illustrated in the patent above mentioned consists generally of a slide on which there is mounted a main tucker finger, together with an additional tucker finger.

The first-mentioned tucker finger will advance a tack to a transfer station, and from this transfer station, the tack is advanced to the attaching station.

Thus after the initial tack is advanced to the transfer station, on a forward stroke of the tucker mechanism, the tack at the transfer station is advanced to the attaching station while a following tack is advanced to the transfer station.

As may also be seen from Figures 2 and 3 of the patent above referred to, one side of the guideway for the tack after it had left the chute consisted of a pivoted jaw, and this jaw has formed on its inner surface a notched plate to temporarily hold a tack at the transfer station.

The main purpose of having the jaw pivoted was that if there was a jam of the tacks on the table, that is, after the tacks had left the chute on their travel to the attaching station, the pivoted jaw could be swung outwardly and the offending tack removed by hand. Also it was necessary that the jaw pivot on the advancement of every tack to the attaching station.

However, there arose certain disadvantages in having this pivoted jaw forming a part of the attaching station and moving on the advancement of each tack, and, therefore, an object of the present invention is to so arrange the tucker mechanism and transfer station that the pivotal emergency jaw may still be moved should the tacks become jammed on their way to the attaching station or the transfer station, but the pivoted jaw is in no way actuated by the normal operation of the tack as it passes to the transfer station and to the attaching station.

Still another object of the invention is to provide a gate adjacent to one side of the trackway

for the tracks, so that the gate will be operated by a tack on its way to the transfer station and securely hold the tack until such time as it is forced by the finger of the tucker mechanism out to the transfer station, and likewise the pivoted jaw will always remain in its normal position unless moved by hand to clear an offending tack from the trackway.

With these and other objects in view the invention consists in certain new and novel arrangements and combination of parts as will be hereinafter more fully described and pointed out in the claims.

Referring now to the drawings showing a preferred embodiment:

Figure 1 is a fragmentary view of a tack chute of a button-attaching machine, together with a part of the tucker slide mechanism and showing a tack at the transfer station and a tack on the anvil (attaching station) directly beneath the button-holding jaws and plungers;

Figure 2 is a fragmentary top plan view of a portion of the tucker slide and showing my new and improved transfer station;

Figure 3 is a fragmentary view similar to Fig. 1 but with the tucker block retracted to permit the second or additional finger to spring up behind the tack positioned at the transfer station ready to advance this tack;

Figure 4 is a side elevation of the tucker slide unit;

Figure 5 is a rear elevation of this tucker slide unit;

Figure 6 is a rear view of the block or table holding the tucker slide;

Figure 7 is a fragmentary top plan view of the raceway with parts removed for sake of clearness of illustration;

Figure 8 is a detail of the pivotal gate;

Figure 9 is a side elevational view of same; and

Figure 10 is a top plan view on an enlarged scale of a button to be secured by a tack positioned over the attaching station.

At the outset it might be mentioned that only that part of the machine is shown which is thought necessary to illustrate the present invention, and if a more detailed description of the type of machine is desired reference may be had to my patent above mentioned, to wit No. 2,265,575 of December 9, 1941.

It might also be mentioned at the outset that the tucker slide unit and its mechanism is the same as that shown in the patent above referred to with the exception that I have provided a different form of transfer station, so that it will be unnecessary for the emergency jaw to swing slightly outwardly each time a tack is forced from the chute to the transfer station and from the transfer station out to the attaching station.

In this way I provide what might be termed a stationary track for the tack as it passes from the chute to the transfer station, and from the transfer station to the attaching station. It is true that a pivoted gate of the transfer station swings outwardly and then snaps inwardly every time a tack is advanced to the transfer station or from the transfer station to the attaching station, but this pivoted gate is supplemental to the side wall of the track, as will be seen as the specification proceeds.

Now referring to Fig. 1, there is fragmentarily shown a tack chute 1, which leads from the hopper (not shown) for the tacks to the table 2, in which operates the tucker slide and on which the tacks are deposited one at a time by an escapement 3 in the tack chute.

At the outer end of the table 2, in which the tucker slide operates, is the anvil 4, which is often spoken of as the attaching station. The escapement (not shown in detail) in the tack chute, which escapement is operated by the tucker slide, permits only one tack to be released from the chute to the table 2 on each upward movement of the plunger 3'.

It will be understood that the action of the tucker slide is synchronized with the operating mechanism (not shown) of the plunger, so that on every upward movement of the plunger, there is a forward movement of the tucker slide to thus assure that a tack will be liberated to the table and advanced out to the attaching station.

Then, on every descent of the plunger, there will be a tack at the attaching station to be forced through the cloth into the button.

Referring particularly for the moment to Fig. 4, there is shown in detail the tucker slide unit, which slides within the table 2, which, it will be remembered, is just beneath the end of the tack chute 1.

The unit consists of the block 5, which is substantially T-shaped in cross section and has the tucker finger 6 mounted thereon, which finger is slightly concaved out at its forward end, so that the nose 7 will partly encircle the shank or prong of the tack and the undercut 8 in the finger will clear the head of the tack, as seen in Fig. 1. On the under surface of the block or slide 5, there is a post 5' which is connected to an arm 5a of the operating mechanism for advancing and retracting the slide in the table 2.

So far the tucker slide block and its tucker finger are very similar to those shown in the patent to F. H. Peterson, #2,265,575 of December 9, 1941.

There will be noticed an auxiliary pivoted finger 9 fitting within the forward end of the block 5, the pivotal point 10 being just slightly in advance of the forward end of the tucker finger 6.

Also there may be seen the downwardly extending arm 11, which forms a part of the finger 9 to which is secured the spring 12, which, in turn, is secured to the post 13, so that this finger 9 normally assumes a tilted position, as shown in Fig. 4. The finger 9 also has its nose slightly concaved, as at 14, to partly encircle the prong of a tack, as will be readily understood.

It will be noticed that this tucker finger 9 extends out beyond the forward end of its block, as seen in Fig. 1, so that the tack when advanced will be positioned out on the anvil 4 directly beneath the plunger 3' and button-holding jaws 3''.

Near the rear end of the block 5, as may be

seen in Patent No. 1,567,882 issued to Franklin R. White, on December 29, 1925, is the downwardly extending lug 15 together with a bolt 16. Extending outwardly from the lug is a stud 25 with a roller sleeve thereon which is associated with a cammed bell-crank element, which element has the horizontally extending locking finger 17, as may be seen in Fig. 1, while at the rear of the element may be seen the block 18. Also there is the upwardly extending arm 19 which is pivoted to the further arm 20 having a terminal portion as at 21, which in turn embraces a rod 21' that operates the escapement 3 in the tack chute. Thus, when the tucker slide is retracted its full extent, the finger 17 of the bell-crank element is unlocked and swung downwardly from its pivotal point by the contact of the stud 25 striking the block 18. The arm 19, being pulled downwardly, operates the escapement 3 through the aforementioned arm 20 and the rod 21' and liberates a tack from the escapement 3 in the chute 1 to the table 2.

It will be understood that as long as the stud 25 underlies the forward portion of the finger 17, the tack escapement 3 is held in a locked condition, that is, in a position to cut off descent of tacks.

This mechanism, which is shown in Figs. 1 and 6, is similar to that shown in the former White Patent No. 1,567,882 mentioned, with the exception that there is an additional arm 20 that connects through the arm 21 with the rod 21' to operate the escapement rather than being connected directly to the rod 21', all as shown in Patent No. 2,265,575 earlier referred to.

The pivoted finger and escape mechanism are the same as in my prior Patent #2,265,575 of December 9, 1941.

Referring now for the moment to Fig. 2, there is seen the emergency pivoted jaw 22 on the table 2 that extends out to the attaching station, and this jaw together with the opposite stationary side wall forms the raceway for the tack along the table to the attaching station, which raceway also bounds the tucker slide fingers on their opposite sides. The purpose of having the jaw pivoted is so that if a tack should become jammed under the tucker finger, the jaw may be swung outwardly and the offending tack removed. There may also be seen the small leaf spring which is positioned partly alongside and partly under the jaw 22 for holding this jaw in its normal position.

Referring now to the gist of the invention and to Figs. 1 and 2 and in detail in Figs. 8 and 9, it will be seen that I have cut out a small portion of the stationary sidewall of the table 2 as at 30, so that there can be fitted therein the gate 31, which is pivoted as at 32. This gate is provided with a nose 33, which is indented as at 34, and it will be seen that there is a cam surface 35 extending along the body of the gate up to the nose and to the indentation heretofore mentioned.

It will also be seen that this cam surface overlies the track or raceway in which operates the heretofore mentioned tucker finger 6, and likewise the additional tucker finger 9.

There will also be seen the small post 36, which is secured to the rear edge of the gate 31, to which post is secured the spring 37, which spring is also connected to the post 38 which is fitted within the edge of the table.

Thus the nose portion of the gate 31 is free to pivotally swung away from the track, and the

gate will assume its normal position as soon as the moving pressure is released.

Thus on a forward movement of the tucker slide after a tack has dropped on the table 2, the finger 6 of the tucker slide will advance the tack to the transfer station, or in other words to the gate 31, and the camming action will push the gate laterally, until the tack is located in the indent of the nose 34 as heretofore mentioned. There it will be held at the transfer station until advanced by the forward tucker finger 9 on the next forward movement of the tucker slide.

Thus it will be seen that the emergency guard or jaw 22 remains in its normal position during the entire movement of the tack from the chute out to the attaching station. The only time that this jaw will be moved is when it is desired to remove an offending tack which may have jammed in the raceway.

Thus the track walls on both sides of the prong of the tack, that is the side walls, remain in a fixed position so that the tack may be properly advanced by the respective tucker fingers.

Briefly, the operation of the tucker slide is as follows:

On a downward stroke of the plunger 3', the tucker slide is retracted by suitable mechanism (not shown), of which the arm 5^a is the end element and is connected to the stud 5' through which said arm 5^a retracts the tucker slide. As the tucker slide reaches its rearmost end of travel, the stud 25, which underrides the cam finger 17 (Fig. 1) to thus normally hold the escapement locked, strikes the block 18 of the cammed bell-crank element and pushes down the rod 21' to, in turn, swing the escapement in the tack chute 1 and liberate a tack to the table 2. Then, as the plunger 3' rises, the tucker slide begins its forward stroke and the finger 6 engages the prong of the liberated tack and forces it outwardly to the position shown in Fig. 2 to the transfer station or, in other words into the indent 34 of the nose 33 of the gate 31. After the tack is advanced to the attaching station the gate will spring back to its normal position.

Of course, when the machine is first started, there will not be a tack at the transfer station to be carried out to the attaching station. However, after the first tack has been deposited out on the transfer station, when the tucker slide next advances not only will the tucker finger 6 advance a tack to the transfer station but the finger 9 of the tucker slide will also advance the tack from the transfer station out to the attaching station, as seen in Fig. 1.

This is accomplished due to the fact that on the rearward stroke of the tucker slide, the forward finger 9 will be forced from its tilted position to a horizontal position, as the tack cannot be moved vertically or rearwardly and the head will, therefore, act as a cam to cause the finger 9 to move down to a horizontal position until it has passed under and to the rear of the tack on the transfer station. When once past this point, the finger 9 will spring upwardly, and then on the forward stroke of the tucker slide, the finger engages and will advance the tack out to the position shown in Fig. 1.

Thus, after the first tack has been deposited on the transfer station, at every forward movement of the tucker slide one tack will be carried

from the chute out to the transfer station while the tack at the transfer station will be carried out to the attaching station.

It will be appreciated that I have only fragmentarily shown the attaching plunger and the holding jaws for the buttons, as those portions of the machine that handle the buttons form no part of the present invention per se. Also it will be understood that different forms of tack buttons may be used. In Fig. 10, I have shown an enlarged face view of a button 26, which is provided with suitable insignia 27 and having a specially shaped hub 28, on which are the flat surfaces 29 and 30' and the aligning wall 31', all arranged at a 20° angle to the vertical position of the insignia to insure the button being delivered to the attaching station with its insignia in properly readable position when being attached to the garment. The button illustrated is shown in detail in Patent No. 2,170,092, granted to Rollin R. Clarke and me on August 22, 1939, for Tack buttons.

From the foregoing it will be seen that I have provided a tucker mechanism that has all the advantages of the tucker mechanism mentioned in my former patent, to wit No. 2,265,575, together with the further advantages that the emergency jaw which forms one side of the track for the tack is not moved on every movement of the tucker slide. On the contrary, it remains rigid and forms a guide wall for the tack on its passage from the chute to the final attaching station, and only has to be swung when necessary to free an offending tack from the track, which infrequently happens. Finally the movement of the gate 31 in no way affects the rigidity of the opposite side wall that forms the remaining side of the raceway.

It will be understood that although I mentioned registrable buttons the mechanism can just as well be used with non-registrable buttons and that it is within the purview of the invention to feed and deliver staple fasteners as well as single prong fasteners.

Having thus described my invention, what I claim as new and desire to secure by Letters Patent is:

In a tucker mechanism for a button-attaching machine, a raceway for the tacks, one side of the raceway comprising an undercut pivotal emergency jaw together with a relatively heavy spring for holding the jaw in place, the other side of the raceway comprising a fixed undercut wall, a transfer station associated with the fixed wall, said transfer station including a pivotal gate having an indented nose extending over said raceway, spring means associated with the pivotal gate for holding the same in its normal position, tucker means for advancing a tack along said raceway, the spring associated with the pivotal jaw being unyielding throughout the movement of the tack and holding said pivotal jaw in its stationary position, the pivotal gate being adapted to swing away from the tack to release the tack on each forward movement of the tucker means, and the said pivotal emergency jaw being adapted to be manually swung away from said pivotal gate in case the tacks become jammed in the said raceway.

FREDERICK H. PETERSON.
